CLAIM

The ornamental design for a combined bicycle sprocket and deflector plate, substantially as shown and described.

DESCRIPTION

FIG. 1 is a side elevational view of a combined bicycle sprocket and deflector plate showing my new design; FIG. 2 is a side elevational view thereof opposite to that shown in FIG. 1;

FIG. 3 is a top plan view thereof;

FIG. 4 is an end elevational view thereof;

FIG. 5 is a greatly enlarged cross-sectional view thereof taken along line 5—5 in FIG. 2;

FIG. 6 is a side elevational view of a combined bicycle sprocket and deflector plate showing a second embodiment of my new design;

FIG. 7 is a side elevational view of the side opposite to that shown in FIG. 6;

FIG. 8 is a top plan view of FIG. 6; and

FIG. 9 is an end elevational view of FIG. 6.

FIG. 1.

FIG. 3.

FIG. 2.

FIG. 4.

FIG. 5.

FIG. 6.

FIG. 7.

FIG. 8.

FIG. 9.
